UNITED STATES PATENT OFFICE.

HARRY C. CLAY, OF COLUMBUS, INDIANA, ASSIGNOR TO REEVES & CO., OF SAME PLACE.

DESIGN FOR A SEPARATOR OR CLOVER-HULLER TOOTH.

SPECIFICATION forming part of Design No. 29,894, dated December 27, 1898.

Application filed October 7, 1898. Serial No. 692,955. Term of patent 14 years.

To all whom it may concern:

Be it known that I, HARRY C. CLAY, a citizen of the United States, residing at Columbus, in the county of Bartholomew and State 5 of Indiana, have invented and produced a new and original Design for Separators or Clover-Huller Teeth, of which the following is a specification.

The accompanying drawings illustrate my 10 design for separator or clover-huller teeth.

Figure 1 is a perspective view of my design. Fig. 2 is a side elevation. Fig. 3 is an under plan view.

In the drawings, 4 indicates the upper portion 15 of a separator or clover-huller tooth. At

the base of the portion 4 is the base of an inverted truncated hexagonal pyramidal portion 6, from the apex of which extends the shank 5.

The essential feature of my design is the 20 truncated pyramidal portion 6, which lies between the upper portion 4 and the shank 5.

I claim as my invention—

The design for a separator or clover-huller tooth, substantially as shown and described. 25

HARRY C. CLAY.
